It is certified that error appears in the above-identified patent and that said Letters Patent is hereby corrected as shown below:

Delete the title page showing an illustrative figure and substitute the attached title page
therefor.

In the Drawings

Please delete issued FIG. 1 from this patent and insert in lieu thereof the FIG. 1 as
originally-filed in the application, a copy of which is attached.

Signed and Sealed this
Twenty-seventh Day of January, 2015

Michelle K. Lee
Deputy Director of the United States Patent and Trademark Office
